(57) **CLAIM**

The ornamental design for a lamp, as shown and described.

DESCRIPTION

FIG. 1 is a top and front perspective view of a lamp showing a first embodiment of my new design;

FIG. 2 is a front elevational view thereof;

FIG. 3 is top plan view thereof;

FIG. 4 is a bottom plan view thereof; and,

FIG. 5 is a top and front perspective view of a lamp showing a second embodiment of my new design.

The broken-line disclosure in the views is understood to represent a portion of the article in which the claimed design is embodied, but which forms no part of the claimed design.
